US00D539719S

(12) **United States Design Patent** (10) **Patent No.:** **US D539,719 S**
Aoki (45) **Date of Patent:** **** Apr. 3, 2007**

(54) **WHEEL**

(75) Inventor: **Masafumi Aoki**, Toyota (JP)

(73) Assignee: **Kosei Aluminum Co., Ltd.**, Aichi (JP)

(**) Term: **14 Years**

(21) Appl. No.: **29/212,805**

(22) Filed: **Sep. 8, 2004**

(51) LOC (8) Cl. **12-16**

(52) U.S. Cl. **D12/209**

(58) Field of Classification Search D12/204-213;
301/37.101, 64.101, 65

See application file for complete search history.

(57) **CLAIM**

The ornamental design for a wheel, as shown and described.

DESCRIPTION

FIG. 1 is a front perspective view of a wheel showing the new design;

FIG. 2 is a front elevational view thereof;

FIG. 3 is a top plan view thereof, the bottom plan view being identical thereto;

FIG. 4 is a front perspective view of a second embodiment of a wheel showing the new design;

FIG. 5 is a front elevational view thereof; and,

FIG. 6 is a top plan view thereof, the bottom plan view being identical thereto.

CERTIFICATE OF CORRECTION

PATENT NO. : Des. 539,719 S
APPLICATION NO. : 29/212805
DATED : April 23, 2007
INVENTOR(S) : Masafumi Aoki

Page 1 of 6

It is certified that error appears in the above-identified patent and that said Letters Patent is hereby corrected as shown below:

The Title Page, showing an illustrative figure, should be deleted and substitute therefor the attached title page.

Delete drawings sheets 1-4 and substitute therefor the drawing sheets, consisting of figs. 1-6 as shown on the attached page.

Signed and Sealed this

Twentieth Day of November, 2007

A handwritten signature in black ink, appearing to read "Jon W. Dudas". The signature is written in a cursive style with a large, stylized "J" and "W".
